UNITED STATES PATENT OFFICE.

ROBERT SCHEY, OF NEW YORK, N. Y., ASSIGNOR TO NATHAN H. RICH & BRO., OF NEW YORK, N. Y., A FIRM CONSISTING OF NATHAN H. RICH AND MAURICE RICH.

DESIGN FOR A PRINTED FABRIC.

Application filed November 20, 1925. Serial No. 15,484. Term of patent 3½ years.

To all whom it may concern:

Be it known that I, ROBERT SCHEY, a citizen of the United States of America, and a resident of the city of New York, borough of Manhattan, in the county and State of New York, have invented a new, original, and ornamental Design for a Printed Fabric, of which the following is a specification,

Reference is to be had to the accompanying drawings in which the figure is a plan view of a swatch of fabric showing my new design.

I claim—

The ornamental design for a printed fabric as shown.

ROBERT SCHEY.
